Amer. off. or advertisingly vilalibary form technic
entitled "A method of making a wire having a
constant resistance per unit length and a
constant resistance per unit area."

UNITED STATES PATENT OFFICE.

DAVID E. SHAW, OF MILWAUKEE, WISCONSIN.

Inventor of a new and useful UTENSIL.

See or Am. off. or advertisingly vilalibary form technic
entitled "A method of making a wire having a
constant resistance per unit length and a
constant resistance per unit area."The invention relates to electrical heating
apparatus, and more particularly to uten-
sils for domestic or industrial use.

The object of this invention is to use a
heating element comprising a conducting
wire of low resistivity or very good conduc-
tivity, and preferably one having a positive
temperature coefficient of resistance, such as
a single substantially pure metal, the ele-
ment being arranged in closely related
lengths about a receptacle and being small
in cross-section so that a great number of
lengths or turns may be made on the uten-
sil or receptacle to be heated for a given
current consumption in order to secure a
greater contacting surface. In order also
to further increase the transfer of heat by
conduction the element is brought into very
close relation with the walls of the recep-
tacle to be heated and insulated therefrom
by a very thin layer or coating of binding
material, and the wire preferably used is
one having a thin enamel insulation coat-
ing. The turns of this wire are practically
in contact with each other and the exposed
portions of the element are shut off from the
air or other gaseous medium by a coating
of insulating material. With this con-
struction I have found that the current con-
sumed in doing a given amount of cooking
in the container embodying the invention is
much less than is usual in electrical cooking
utensils.

A further object of the invention is to pro-
vide an electrical heating apparatus having
outer and inner receptacles, the heating ele-
ment being mounted on the inner receptacle
and the space between the receptacles within
which the element is enclosed having the
air exhausted therefrom.

A further object of the invention is to
provide an electrical heating apparatus in
which variable heat may be imparted to the
container by varying the circuit arrange-
ment for the heating element.

A further object of this invention is to
provide a heating element in which both
the working and ultimate temperature can
be fixed by properly proportioning two fac-
tors; one being resistance determined by the
length and cross-section of the wire consti-
tuting the active element, and the other be-
ing resistance developed by the use of a wire
having a high positive temperature coeffi-
cient of resistance and the consequent de-

crease in the consumption of current as the
temperature developed therein increases.
By the proper choice of these factors, I can-
struct each utensil so that it will do the
character of cooking it is designed for 60
quickly, and can control it so that it will
not develop a temperature sufficiently high
to burn the substance being heated or de-
stroy the heating element or the container
to which it is attached if empty. 65

A further object of the invention is to
arrange the connections between the con-
tainer and the source of current supply so
as to eliminate any danger of shock when
the utensil is touched by a person in contact 70
with the ground.

With the above and other objects in view
the invention consists in the construction
and the several features of construction
hereinafter described and all equivalents. 75

In the drawings: Fig. 1 is a vertical sec-
tional view through a heating appliance
embodying the invention; Fig. 2 is a dia-
grammatic view of the wiring system for
the element. 80

In the drawings I have illustrated a uten-
sil embodying the invention, comprising an
inner receptacle or container 3 and an outer
container 4, the inner container resting upon
the top of the outer container and depending 85
into the same to provide a space 5 between
the containers. I desire it to be understood,
however, that the invention is not to be lim-
ited to the particular form or shape of the
container herein illustrated, as the utensil 90
may be a coffee-pot, a frying-pan, oven, or
other device in which the material subjected
to heating or cooking is placed in the inner
container.

The inner container 3 is preferably of so-
called enamel ware, that is, the metal body
6 has an inside coating 7 and an outside
coating 8 of enamel or other suitable hard-
ened insulating material. 95

The heating element 9 is preferably a very 100
fine wire of high conductivity wound around
the outside of the container 3. By fine wire
I mean a wire on the order of 27 B. & S.
gauge or less. This wire preferably is sub-
stantially mono-metallic so that it has a 105
positive, and preferably high, temperature
co-efficient of resistance, and the convolu-
tions while touching each other are prac-
tically insulated from each other by a very
thin film of insulating material with which 110

the wire is coated. By using a very fine wire such as on the order of No. 27 B. & S. gauge or less, of many turns, or lengths in the case of flat winding, the total length of the wire constituting the heating unit is much greater than each turn thereof; therefore there is very little difference in potential between adjacent turns and consequently an extremely thin coating of insulation applied to the wire may be used to prevent short-circuiting between turns. I have found that a very fine enamelled copper wire satisfies the above requirements and this wire, preferably a single layer, is wound directly on the inner container. Moreover, the enamel is a fair heat conductor and dampness will have no bad effect on windings thus insulated. However, as the enamel coating 8 presents a slippery surface, I coat this enamel surface prior to winding with a thin semi-liquid coating of insulating material, such as sodium silicate thickened with whiting, which fills in the exposed spaces between the convolutions of the wire and between the wire and the container, and which hardens as soon as it is subjected to the heat developed by a current of proper strength passing through the wire, whereby the element is firmly bound in close contact with the receptacle and is cut off from the air or other gaseous medium. By adopting this construction the insulation between the metal and the element and between the convolutions of the element is far thinner than could be obtained by solid insulation, the heat developed in the element is transmitted direct to the metal of the container and thence to the material within it substantially by conduction through this binding material with a very low temperature difference. The utensil is primarily designed for cooking or baking so the ultimate temperature required is never greater than 500° Fahrenheit and it is therefore possible to use insulating material of much lower heat resisting properties than would be the case if the wires were allowed to reach a higher temperature. Furthermore, as the radiating surface of the inner container is relatively much greater than that of the current-carrying heat-producing unit 9 it radiates the heat conducted from the element very readily and is preferably so designed that the maximum temperature developed when the utensil is empty will not be sufficiently high to cause injury to the heating unit or the utensil. Also by using an element having a positive temperature coefficient of resistance the resistance of the wire increases as the temperature rises so that the current consumption decreases as the temperature of the receptacle and its contents rises.

Another fact to be noted in connection with this construction is that the quantity of heat developed by the element is greatest

when the container and its contents are coldest and gradually diminishes as the temperature of the whole mass rises, and since the element is so closely associated with the receptacle that there is little difference between the temperature of the element and the contents of the receptacle the desired temperature is rapidly attained.

The heating element 9 is preferably formed in sections A and B and wired so as to produce low, medium or high heat. For this purpose I arrange three sets of plugs on the receptacles, one set comprises plugs 11 and 12 for the low heat, another comprising plugs 13 and 14 for the medium heat and another set comprising plugs 15 and 16 for the high heat, the plug 16 being a split plug having one half 16" insulated from the container and the other half 16' grounded on the container. One end of section B is in circuit with the plugs 12 and 14 and the part 16' of the plug 16, the element 20' representing such plugs in Fig. 1, and being directly secured to the container by nuts 23'. A conductor 18 connects the plugs 13 and 15 with the sections A and B and a conductor 19 connects the plug 11 and the other part 16" of the plug 16 with one end of the section A. With this construction when the supply circuit is connected to the plugs 11 and 12 current passes from the plug 11 through the conductor 19, sections A and B to plug 12, containers 3 and 4 to plug 12. When the supply current is connected to the plugs 13 and 14 current passes from the plug 13 to conductor 18, section B, the containers 3 and 4 to plug 14. When the supply circuit is connected to the plug 15 and 16 current passes from the plug 15 through conductor 18 from which part of the current flows through section B to containers 3 and 4 and thence to part 16', and part of the current flows through section A to part 16" of the plug 16, as will be apparent when the connections for the plugs are described.

The insulating plugs 11, 13, 15 and 16 each comprise a member 20, preferably made hollow so that the wires connected with these plugs may be drawn through the openings in such plugs. These members are secured to the outer container in any suitable manner, as by washers 21 and 22 of insulating material and clamping nuts 23. The plugs 12, 14 and 16' each comprise a member such as 20' connected directly to the container by nuts 23' or other suitable means. A passage in one of the hollow plugs above described may be used for the purpose of exhausting air from the space 5, the outer ends of each of these hollow plugs being sealed by a plug 25 or other suitable means. By providing a vacuum space between the containers heat conduction losses from the inner to the outer container are minimized and to

effectually seal the containers together the upper beaded edge 26 of the container 4 is pressed into and interlocked with an annular groove 27 formed on the inner container. In the split plug it will be understood that the parts 16' and 16'' are suitably separated from each other by insulating material.

In each instance connection with the supply circuit 28 and 29 is made by a fixed contact 30 and a flexible contact 31, respectively, connected to the wires 28 and 29. Either set of plugs is adapted to be pushed into contact with supply contacts, as indicated in Fig. 2, but the lower plug is made longer so that the ground connection through the contact 31 is made first when the utensil is pushed along the support 32 to bring the desired plugs into engagement with the contacts 30 and 31. As contact 31 is resilient it will act to press the upper plug into engagement with the fixed contact 30 as well as make a good contact with the lower plug. The grounded side of the line is always connected to contact 31 so that there will be no voltage difference between the container and the ground under any conditions.

I desire it to be understood that this invention is not to be limited to any specific form or arrangement of parts except in so far as such limitations are specified in the claims.

What I claim as my invention is:

1. In an electrically-heated utensil, the combination with a heat-conducting container, of a heating element comprising a copper wire coated with a very thin heat-conducting, moisture-proof insulating film, said wire being closely wound with contiguous convolutions about said container, and means for supplying current to said element.

2. In an electrically-heated utensil, the combination with a heat-conducting container, of a heating element comprising a fine enamelled wire of substantially pure copper wound with contiguous convolutions in close thermal relation to said container,

and means for supplying current to said wire.

3. In an electrically-heated utensil, the combination with a container, of a fine closely wound copper wire wound directly upon the container, a very thin film of insulation spacing adjacent convolutions of the wire, and means for supplying current to said wire. 50

4. In an electrically-heated utensil, the combination of an inner container, an outer container spaced therefrom, the air being exhausted from the space between said containers, a heating element attached to the inner container, and means for supplying current to said element. 55

5. In an electrically-heated utensil, the combination with a container, of a heating element attached thereto, plugs secured to the terminals of said element, one of said plugs being grounded to said utensil, means for supplying current to said element on connection with said plugs, and means whereby the grounded plug is connected to the grounded supply line before the other plug can be connected to the other line. 65

6. In an electrically-heated utensil, the combination of an inner container, an outer container spaced from the inner container, a heating element within the space between said containers and attached to the inner container, and means for exhausting air from the space between the containers including a contact plug secured to the outer container and having an exhausting passage therein. 75

7. In an electrically heated utensil, the combination with a container, of an enamelled copper wire closely wound around said container in close thermal relation therewith, said wire having a gauge thickness of 27 B. & S. gauge or less and a negligible potential difference between turns. 85

In testimony whereof, I affix my signature. 90

DAVID E. SHAW.
